UNITED STATES PATENT OFFICE.

JOHN J. FLANIGAN, OF CHICAGO, ILLINOIS, ASSIGNOR TO DUPLICATOR MANUFACTURING COMPANY, OF CHICAGO, ILLINOIS, A CORPORATION OF WEST VIRGINIA.

MULTIPLE-COPYING MACHINE.

1,118,119.

Specification of Letters Patent.

Patented Nov. 24, 1914.

Application filed May 1, 1911. Serial No. 624,308.

To all whom it may concern:

Be it known that I, JOHN J. FLANIGAN, a citizen of the United States, residing in Chicago, in the county of Cook and State 5 of Illinois, have invented certain new and useful Improvements in Multiple-Copying Machines, of which the following is a specification.

This invention relates to the art of multiple copying machines, or hectographs, as they are sometimes called; and has for its general object to improve machines of this character in the direction of rendering them more reliable and efficient in operation, more 10 specific objects being to provide an improved impression device, to provide an improved means for guiding and supporting the impression device, to provide an improved means for accurately positioning and squaring the sheet of paper with reference to the copying apron or band, and to provide an improved means for preventing slack in the copying apron or band.

In the accompanying drawings I have 15 illustrated one practical mechanical embodiment of my invention, in which,—

Figure 1 is a top plan view of a multiple copying machine constructed in accordance with my invention. Fig. 2 is a side elevation of the same partly broken away; Fig. 3 is an elevation, broken out, of the upper portion of the machine as viewed from the opposite side to that shown in Fig. 2; Fig. 4 is a detail side elevation of a combined detent and brake for the rear or unwinding roll of the copying apron; Fig. 5 is a detail elevation, broken out, of one of the receiving and delivery spools (which are duplicates); Fig. 6 is a fragmentary elevation 20 showing the bearing of the spools in the rear side of the machine frame; Fig. 7 is a bottom plan view of the impression device; and Figs. 8 and 9 are cross-sectional views of the impression device, Fig. 8 showing the same in working position and Fig. 9 showing the same in idle or paper-receiving position.

Referring to the drawings, 6 designates each of a pair of parallel vertical side frame members supported on integral legs 7 and 25 themselves constituting a support for a horizontal bed 8 between them. Stretched over the bed 8 is a felt covering 9, that is overlaid by the gelatin copying apron or band 10, this latter passing around guide-rolls 11 and 12 at the opposite ends of the frame

and being wound on delivery and receiving spools 13 and 14, respectively, journaled in suitable bearings between the side members 6 and beneath the bed 8. The receiving and delivery spools are duplicates of each other, 60 and one of them is illustrated in detail in Fig. 5, from which it will be seen that they are provided at each end with journals 15 and inwardly of the latter with squared portions 16; the two ends of each spool being 65 of duplicate construction so that each is reversible end for end, and when in operative position one end of each spool is engaged with a driving-chuck such as is shown at 17 in Fig. 4; this latter having a transverse 70 slot 18 to receive the squared portion 16 of the spool and, behind the slot, a circular socket 19 to receive the journal 15. The journal 15 at the opposite end of the spool 75 engages a journal-bearing 20 (Fig. 6) that may conveniently consist simply of a semi-circular notch formed in the edge of the side frame member 6; the open end of the notch being guarded by a spring-actuated latch 21 pivoted at 22 on the outside of the rear 80 frame member 6 and formed with an inwardly projecting lip 23 that is movable toward and from the open side of the notch by the swinging of the latch 21 on its pivot, the said latch being normally maintained 85 in operative position by a spring 24 anchored at its upper end to a lug 25 on the frame member 6 and at its lower end connected to a lug 26 projecting inwardly 90 through a slot 27 in the frame member 6. 90

The receiving spool 14 has a driving and detent mechanism comprising the following parts.

28 is a sprocket-wheel lying just inside the front side frame member 6, the shaft of 95 which is suitably journaled in said side frame member and provided on its outer end with a hand-crank 29. A sprocket chain 30 connects the sprocket-wheel 28 with a smaller sprocket-wheel 31, the shaft of 100 which is likewise journaled in the side frame member 6, the inner end of said shaft being formed with a spindle receiving bearing and chuck identical with that shown at 17, 18, and 19 in Fig. 4. Fast on the shaft of the sprocket 31 is a ratchet-disk 32 controlled by a pair of pivoted dogs 33 and 34 designed to lock the receiving spool against back turning movement.

The delivery spool 13 is journaled at one 110

2
end in a bearing such as shown at 20 in Fig. 6, and its opposite end is engaged by the chuck 17, fast with which latter is a ratchet-disk 35 and a brake-disk 36.

5 37 designates a dog pivoted at 38 in the side frame member 6; the tail end of the dog 37 being engaged by the forked end of a lever 39 that is pivoted at 40 to the side frame member 6 and is normally urged upwardly by a spring 41 between said lever and a lug 42 on the frame member 6. The lever 39 has a depending brake-shoe 43 adapted, when the lever is depressed, to engage the brake-wheel 36, and said lever also 10 carries a laterally disposed key 44 (Fig. 2), the shank of which extends through a slot 45 cut in the frame member 6.

From this construction it will be seen that, under the action of spring 41, the dog 37 is 20 normally maintained in engagement with the ratchet 36, preventing unwinding movement of the spool 18; and that by depressing the key 44, the dog is disengaged from the ratchet and the brake-shoe 43 is simultaneously engaged with the brake-disk 36, so that, as the receiving spool is wound up and the delivery spool simultaneously unwound, a proper tension is placed by the brake upon the apron or band, preventing the creation of 25 an undesirable slack therein. As soon as the key 44 is released, the spring 41 instantly retracts the brake and throws the dog into engagement with the ratchet.

On the rear side of the machine and extending parallel with and adjacent to the upper edge of the rear side frame member is a rod 46 that constitutes a guide and support for one end of the impression device. This rod is adjustably supported at its ends 35 between opposed upper and lower adjusting screws 47 and 48, respectively, (Fig. 3) mounted in brackets 49 secured to the ends of the side frame member 6. By this means the guide-rod 46 can be adjusted and leveled 40 very accurately relatively to the bed of the machine.

50 50 designates the substantially rectangular frame of the impression device that extends transversely of and above the bed of the machine and at one end is provided with a widened extension 51 that has a sliding engagement with the guide-rod 46 (Figs. 1 and 3). Within the frame 50 and pivoted on a rod 52 extending between the end walls 55 of said frame is a bail-shaped yoke 53 to the transverse member of which is secured an operating handle 54. Journaled in and between the arms of the yoke 53 is a rubber surface platen roll 55 that co-operates with 60 a gripping roll 56, which latter is journaled in and between the lower ends of a pair of arms 57 that are pivotally hung from screw-bolts 58 secured in the end walls of the frame 50. Compression springs 59 confined between one of the side walls of the

frame 50 and the outer edges of the hanger-arms 57 normally urge the roll 56 inwardly or toward the platen roll 55; so that as the latter is swung downwardly by the handle 54 from the position shown in Fig. 9 to the position shown in Fig. 8, a sheet of paper, indicated at 60, that is entered between the rolls in their open position (Fig. 9) is gripped by and between the rolls and smoothly spread over the surface of the 75 gelatin apron as the impression device is moved bodily longitudinally of the latter, which latter movement may be effected simply by forward pressure on the handle 54 when in the position shown in Figs. 1 and 8. 80 The inward movement of the roll 56 under the thrust of the springs 59 is limited by the engagement of stop-pins 61 (Fig. 7) in the lower ends of the hangers 57 with shoulders 62 formed on the lower edges of the 85 end walls of the frame 50.

63 designates a gravity-lock for maintaining the platen roll 55 and the yoke 53 carrying the same in lowered or working position, said lock being pivoted at 64 to the end 90 wall of the frame 50 and its lower end normally tending to engage a shoulder 65 formed on one of the arms of the yoke 53. Rising from one end of the front side wall 6 (Figs. 1 and 2) is a fixed stop 66 that is 95 struck by a depending arm 67 secured to or integral with the upper end of the lock 63 and overhanging the outer side of one end wall of the frame 50, the engagement of said parts occurring when the impression 100 device has been retracted to its extreme position at the paper-receiving end of the machine, such engagement obviously rocking the lock 63 out of engagement with the shoulder 65, and permitting the backward 105 swing of the handle 54 and yoke 53 and the separation of the rolls 55 and 56, as shown in Fig. 9. The platen roll 55 is positively driven as the impression device is moved bodily over the bed of the machine; 110 the means for this purpose comprising a spirally grooved spool 68 (Figs. 1 and 7) fast on one end of the spindle of the impression roll 55 and lying outside the end wall of the frame 50, said spool engaging a 115 cord 69 secured at one end to one of the brackets 49 and placed under tension by a connection at its opposite end to a helical spring 70 that is anchored to an eye-bolt 71 secured in the rear side frame member 6. 120

One of the side walls of the frame 50 is inclined or outwardly flared, as best shown in Figs. 8 and 9, and to the same is secured a pan or chute 72 that serves to guide the advance portion of the sheet 60 into the impression device and between the rolls thereof; this pan or chute having at one end a stationary end guide wall 73 and at its opposite end an adjustable end guide wall 74 formed on a clip 75 that slidably 125 130

engages the base or bottom of the chute 72, thereby adapting the latter to the accommodation of paper sheets of varying widths.

As an aid in accurately positioning and squaring the paper sheet 60 as it is introduced to the machine, I employ a gage in the form of an angle-bar 76, which is pivoted at one end in a bracket 77 (Fig. 1) secured to the inner face of the rear side frame 6 just in advance of the guide roll 12, and at its opposite end is adapted to rest on a screw 78 tapped into the forward end of the bed 8; this gage-bar thus lying just in advance of the receiving end of the copying band, as best shown in Fig. 1.

On the guide-bar 46 is an adjustable stop for limiting the advance travel of the impression device, the same consisting, as herein shown, of a two-part clamp 79 that is loosened and tightened by a clamp-screw 80, that is adapted to be engaged by the advance end of the extension 51 of the impression device. The frame of the impression device is also provided at its opposite end with a vertical screw 81 (Figs. 1 and 2) threaded through a lug 82 on the end wall of the frame 50 and at its lower end adapted to slidably engage a horizontal way 83 formed on the upper edge of the front side frame member 6. The main function of this screw 81 is to limit the amount of pressure applied to the duplicating band by the impression device in taking a copy. The lower end of the screw 81 is normally just out of engagement with the way 83; but if the operator applies undue pressure to the handle 54 in operating the machine, the lower end of the screw 81 engages the way 83 and thus limits the extent of pressure applied to the duplicating band. The extent of this pressure can be nicely regulated to secure the best results with bands of varying thicknesses, or differing in other qualities, by simply screwing up or down the screws 81, 47 and 48 as may be required. The screw 81 and rod 46 also support the carriage, when open, off the band.

The extension 51 of the frame of the impression device is preferably provided with a pair of downwardly extending prongs 84 (Figs. 1 and 3), which, when the impression device is swung upwardly on the guide-rod 46 as a pivot, engage the rear side frame 6 when the impression device is slightly beyond the vertical position, and thus maintain the latter in elevated position. This is done when it is desired or necessary to wash the duplicating band or replace it by a new band. In one end of the extension 51 is mounted an adjustable stop for the rearward travel of the impression device, the same conveniently consisting of a screw 85 (Fig. 1) provided with a lock-nut 86, and adapted to engage an angular extension 6^a of the rear side frame 6 to bring the rolls

of the impression device in proper position relatively to the gage-bar 76 for receiving the advance end of a sheet of paper. By adjusting the screw 85 the extent of unprinted margin occurring at the forward end of the sheet can be adjusted within certain limits.

The operation of the machine is probably apparent from the foregoing description of its coöperating parts, but may be briefly outlined as follows.

To ink the duplicating band, the impression device is retracted to extreme position, shown in detail in Fig. 9, and the master sheet, from which copies are to be made, is inserted between the rolls of the impression device, the latter being separated as shown in Fig. 9, and the forward edge of the sheet being stopped and squared by the gage 76. The handle 54 being then thrown forward, the sheet is gripped between the rolls 55 and 56 and carried downwardly on to the duplicating band and locked thereon by the latch 63, as shown in Fig. 8. The impression device is then pushed forwardly over the bed 90 of the machine until it engages stop 80, which will be set in accordance with the length of the sheet. The impression device is then retracted, the sheet being fed outwardly by the reverse movement of the rolls 55 and 56 until the extension 67 of the locking latch 63 strikes the fixed stop 66, whereupon the handle 54 swings backwardly separating the rolls, and allowing the paper to be drawn out of the impression device. This same operation is then gone through with the copy sheets, as many copies as desired or possible being taken off; and owing to the devices for accurately guiding and positioning the sheet preliminary to impressing the same upon the duplicating band, it is possible to obtain great accuracy of registration between the matter on the duplicating band and ruled and lined positions on the sheet. When it is necessary to advance the duplicating band to bring a fresh or unused portion thereof into the field of action of the impression device, this is done by simply depressing the key 44, and turning the crank 39; the pressure of the key releasing the dog 37 and simultaneously throwing the brake-shoe 43 on to the brake-disk 36, thereby imparting a sufficient drag to the delivery spool to keep the band taut. When the band has been entirely wound up on the receiving-spool, the two spools and band can be withdrawn, and reversed, the receiving-spool then becoming the delivery-spool and vice versa, the duplicate construction at both ends of each spool 125 spindle making such reversal possible.

I claim—

1. In a machine of the character described, the combination with the frame and bed, of receiving and delivery spools jour-

- naled in the frame, a duplicating band extending over the bed between said spools, means for turning the receiving spool to wind the band thereon, a chuck engaging 5 the spindle of the delivery spool, ratchet and brake-disks fast with said chuck, a brake adapted to engage said brake-disk, a pawl adapted to engage said ratchet-disk and connected to said brake, a spring normally 10 acting to simultaneously retract the brake and engage the pawl, and manually operable means for simultaneously retracting the pawl and applying the brake, substantially as described.
- 15 2. In a machine of the character described, the combination with the frame and bed, of receiving and delivery spools journaled in the frame, a duplicating band extending over the bed between said spools, 20 means for turning the receiving spool to wind the band thereon, a chuck engaging the spindle of the delivery spool, ratchet and brake disks fast with said chuck, a pivotally mounted lever carrying a brake-shoe 25 adapted to engage said brake disk, a spring normally acting to retract said lever and brake-shoe from said brake disk, a pivoted pawl connected to said lever and adapted to be thrown into engagement with said 30 ratchet-disk by the brake-retracting movement of said lever, and a manually operable key connected to said lever for actuating the same in opposition to said spring, substantially as described.
- 35 3. An impression device for a hectograph machine, comprising, in combination, a frame, a yoke pivotally mounted in said frame, a platen-roll journaled in and between the arms of said yoke, an operating 40 handle for said yoke, and a spring-pressed bodily yieldable gripping-roll mounted in said frame independently of said yoke and adapted for coöperation with said platen roll, substantially as described.
- 45 4. An impression device for a hectograph machine, comprising, in combination, a frame, a yoke pivotally mounted in said frame, a platen-roll journaled in and between the arms of said yoke, an operating 50 handle for said yoke, a pair of arms pivotally mounted in said frame independently of said yoke, a gripping-roll journaled in and between the free ends of said arms, and springs engaging said arms in a manner to 55 urge said gripping-roll toward said platen roll, substantially as described.
- 60 5. An impression device for a hectograph machine, comprising, in combination, a frame, a yoke pivotally mounted in said frame, a platen-roll journaled in and between the arms of said yoke, an operating
- handle for said yoke, a pair of arms pivotally mounted in said frame independently of said yoke, a gripping-roll journaled in and between the free ends of said arms, 65 springs engaging said arms in a manner to urge said gripping-roll toward said platen-roll, and means automatically locking said yoke against movement when swung to carry said platen-roll into working position, substantially as described. 70
6. In a machine of the character described, the combination with a frame and bed, and a duplicating band supported on the latter, of an impression device adapted 75 to operate over said band, a rod adjustably mounted on one side of said frame parallel with said duplicating band and slidably engaged by one end of said impression device, a way formed on the opposite side of said frame, and a vertically adjustable bearing member carried by the opposite end of said impression device adapted to coöperate with said way to limit the pressure exertible upon said band through said impression device, 80 substantially as described.
7. In a machine of the character described, the combination with the frame and bed, and a duplicating band mounted on the latter, of an impression device slidably 85 mounted on said frame above said band and carrying paper-feed rolls suitably mounted therein and means for separating and closing said feed-rolls, a stop limiting the extent of movement of said impression device 90 toward the receiving end of the machine, and a gage-bar disposed across the receiving end of the bed and serving to position the advance edge of a sheet introduced between the feed-rolls of said impression device, 95 substantially as described. 100
8. In a machine of the character described, the combination with the frame and bed, and a duplicating band mounted on the latter, of an impression device slidably 105 mounted on said frame above said band and carrying paper-feed rolls suitably mounted therein and means for separating and closing said feed rolls, a stop limiting the extent of movement of said impression device 110 toward the receiving end of the machine, and a gage-bar disposed across the receiving end of the bed and pivoted at one end relatively to the latter, said gage-bar serving to arrest and square the advance edge 115 of a sheet introduced between the feed rolls of said impression device, substantially as described.
